UNITED STATES PATENT OFFICE.

WILLIAM E. PRINDLE, OF MANITOWOC, WISCONSIN.

DRIER.

1,056,121.

Specification of Letters Patent. Patented Mar. 16, 1913.

Application filed April 10, 1912. Serial No. 339,807.

To all whom it may concern:

Be it known that I, WILLIAM E. PRINDLE, a citizen of the United States, residing at Manitowoc, in the county of Manitowoc and State of Wisconsin, have invented certain new and useful Improvements in Driers, of which the following is a specification.

My present invention relates generally to mechanical driers, or more particularly to that type of apparatus designed for use in drying wet materials, such, as for example wet salt, and so forth.

It has for its primary objects the provision in a drier of the character described of improved means whereby the moist vapors resulting from the application of heat to the wet material therein are collected and carried off in such a manner as to assist in the further drying of the material; the provision of an improved arrangement of intake and discharge mechanism whereby flow of the hot gases is maintained in the proper channel of circulation; the provision of an improved flue or vent for conducting the moist vapors from the drier; the provision of a flue within a drier, one end of which continues through the drier to a suitable exhaust means, and is provided with a ferruginous front end and other supplementary means providing communication with the drier at points intermediate its length, for the purpose of carrying away to the atmosphere the heavy moist vapor resulting from the application of hot air or gases to the wet material in the drier; the provision of deflecting means in a drier designed to deflect hot air or vapor to the periphery of the drier thereby securing a maximum efficiency of the heat utilized; and the provision of an improved arrangement of drier which is simple and practical and economical in operation.

These together with such other objects as may hereinafter appear or are incidental to my invention I attain by means of a construction illustrated in preferred form in the accompanying drawings, wherein:

Figure 1 is a longitudinal section of my improved apparatus, in which the outer cylinder is shown partly broken away to disclose the inner tube.

Figure 2 is a sectional view on the line II--II of Figure 1.

Figure 3 is a section through lines

III--III of Figure 1, showing the intake or front end of the inner tube.

In drying wet materials in mechanical driers, it is well known that the application of heat to the wet material results in the formation of a heavy moist vapor, which if allowed to remain in contact with the wet substance materially retards the evaporation of the remaining moisture therefrom. Heretofore, in the ordinary types of mechanical driers employed for this character of work, no adequate means has been provided to properly conduct the moist vapors from further contact with the material therein, and which has in a great measure detracted from the general efficiency of these machines. Through certain improved means, more fully hereinafter set forth, this heavy moisture is withdrawn from further contact with the material to be dried. These means include a perforated inner tube within a drier which has indirect access to the atmosphere. The intake of this inner tube is positioned at a point where this damp vapor would most naturally arise, and the vapor is drawn into the tube by means of an exhaust fan, so that the moisture is held from further contact with the material. The radiation of heat from this vapor tube effectually drives all the remaining moisture from the material in its progression toward the discharge end. The material is dry when it reaches the discharge end of the drier and as the air is practically stationary at this point, no dust can be carried out by the air.

Referring to the drawings illustrating my preferred construction, I provide a drier A which comprises the outer cylinder B and the inner tube C. The inner cylinder C is caused to rotate with the cylinder B by the connecting spider 4. The outer ends of the spider 4 are bolted to the outer shell B and its inner ends to the inner tube C. A spider 5 supports the front end of the tube C, the inner ends of the arms being bolted to a ring 6 which fits easily around the tube C, allowing for any longitudinal expansion or contraction of the said tube.

The drier preferably lies at an angle, the horizontal and rotates in the usual manner by tires 7 engaging with rollers 8, which are mounted on the bases D and are driven from any suitable source of power. At the

forward end of the drier is a stationary feed spout 10 having bearings 11 in which the front end of the drier revolves. Within the feed spout is a damper 9 which is normally held in closed position by the weighted arm 12. Arranged within the forward end of the drier and securely attached to the stationary feed spout is a scraper 13, so positioned that no wet material can adhere to or 5 bake on the shell of the drier. The rear or discharge end of the drier rotates within a stationary hood 14 which is securely mounted on the base E, the hood being further provided with the counter weighted damper 15 at its lower end. This damper is normally closed until the weight of the dried material ready to be discharged counterbalances the weighted arms 16 and 17. F is a suitable source of heat from which heat is 10 drawn into the drier A through the opening G.

The wet material entering the slowly revolving drier through the feed spout 10 is cascaded by the lifting blades 18 and 19, bolted to the inside of the outer shell and the outside of the inner shell respectively. Any baking of the material on the shell is prevented by the scraper 13. The material is at 15 its wettest stage on entering the drier and coming into immediate contact with the gases of a high temperature, the formation of a heavy moist vapor naturally results, which in a drier is a detrimental feature in that further parting of moisture from the 20 material in its progression is retarded.

One of the chief objects of this present invention is to remedy this serious defect in driers heretofore used, to provide for the immediate removal of this moist vapor, to prevent its further contact with the material, and at the same time to fully utilize all the 25 heat therein contained.

The inner tube C is concentrically arranged within the outer cylinder B and preferably rotates with the cylinder B. The flared intake or front end 20 is positioned at a suitable distance from the feed end of the cylinder B, and is provided with performances or openings 21 as shown in Figure 3. The tube proper comprises two sections 22 and 23, and as shown in the preferred construction, the rear section 23 is of less diameter than the forward section 22. The section 23 projects into the section 22 and is 30 spaced away therefrom by any suitable means, such as for example, channels, so that openings 24 are provided between the sections for the further admission of vapor into the tube C. In order to prevent any material caught on the channels 19 from working into the tube C through the openings 24, an annular flange or baffle collar 25 is bolted on the outside of the section 23 adjacent to the openings 24. The rear end of the section 35 23 flares outwardly at 26 and projecting

slightly therein is, what might be termed an extension 27 of the tube C, providing closed communication between the said tube and exhaust fan 28. This extension 27 preferably passes through the stationary hood 14 to meet the flared portion of the tube C. The flared portion 26 is foraminous, in that small peripheral openings 29 are provided for the discharge of any material which may have worked into the inner tube.

The extension 27 is stationary, the tube C revolving about its forward end, leaving a narrow annular aperture 30 at the place of juncture in order that the air at the rear end of the drier A be maintained in circulation. The circulation maintained must necessarily be slight as the material at this point is dry, and it has been found that light particles are not carried out through the tube by the exhaust fan through this aperture 30.

Positioned within the tube C to the rear of the intake 20 is a baffle plate 31 supported by radial arms 32 which are bolted to the inside of the shell. All or most of the vapors are drawn by the fan into the tube through the intake and striking the baffle plate 31 are forced to the periphery of the tube, thus directing more heat to the shell against which the cascaded material comes into contact while the drier is rotating. As the remaining portion of the moist vapors passes through the openings 24 another baffle 31' is similarly located in the section 22.

The operation of the device is substantially as follows:—

The hot air or gases pass through the opening G from the furnace or source of heat F and come into immediate contact with the wet material which is fed into the drier through the feed spout 10. Most of this moist heavy vapor formed at or near this point of contact is drawn into the inner tube C through the openings 21 in the flared front end 20 and in passing through the tube comes into contact with the baffle plate 31 deflecting the hot vapors to the periphery of the tube. The material in its progression rearward is then cascaded by the lifting plates located on both of the cylinders and dried by the heat in the tube. Any remaining moist vapor is drawn through the intermediate openings 24 by means of the exhaust fan and is in turn deflected peripherally by the baffle 31'. The entire operation is continuous, and in the highest sense, simple and economical.

Having thus described my invention and illustrated its use what I claim as new and desire to secure by Letters Patent is the following:—

1. In a rotary drier, the combination of an outer cylinder provided with an opening in the front end thereof leading to a source of hot air, an inner shell mounted in the outer shell adapted to conduct the hot air

rearwardly through the drier and having an inlet opening at its front end substantially in line with the said opening in the outer cylinder.

5 2. In a drying apparatus, an outer shell, an inner shell constituting a flue mounted concentrically and entirely therein and provided with an opening in its front end communicating with the outer shell and exhaust means communicating with the inner shell through the discharge end of the drier, substantially as described.

10 3. In a mechanical drier, the combination of an outer shell having a feed opening provided in its front end and a discharge opening in its rear end, an inner shell mounted therein and rotatable therewith, and deflecting means positioned within the inner tube.

4. In a drier provided with a suitable 20 source of heat, the combination of an outer cylinder provided with an opening at its front end leading to the source of heat, a discharge opening in its rear end, an inner cylinder and a baffle plate mounted within the inner cylinder whereby the heat is deflected to the periphery of the drier.

5. The combination in a drying cylinder and an exhaust fan, of a flue positioned within the said cylinder having its front end 30 communicating with the drying cylinder at a point intermediate the ends of the cylinder, and a connection between the exhaust fan and the other end of the flue in the manner set forth.

35 6. In a rotatable drier the combination with an outer cylinder, of a flue mounted concentrically within the outer shell with its rear end extending to the rear end of the outer cylinder, and a flared intake at the front end of the flue positioned intermediate the ends of the outer cylinder.

7. In a mechanical drier the combination of an outer shell, a feed opening in the outer shell, a stationary hood at the rear end 45 thereof and provided with a discharge opening therein, an inner tube projecting into the outer cylinder and through the said hood, and exhaust means having communication with the outer tube through the inner tube.

8. In a mechanical drier the combination of an outer shell having a feed opening therein and a discharge opening provided at the rear end thereof, an inner tube projecting into the outer cylinder, suction means having communication with the outer tube through the inner tube, and a baffle plate in the inner tube.

9. In a drier, an outer cylinder and an inner cylinder, said inner cylinder being provided with a perforated opening at its front end, an exhaust fan, and a connection between the rear end of the inner tube and the said exhaust fan.

10. In a drier the combination with an

outer cylinder, of an inner tube comprising two sections connected together, one section being of lesser diameter than the other, an opening at the front end of the said tube, said tube being provided with openings between the two sections at their point of jointure, exhaust means located outside of the drier, and connections between the inner tube and the exhaust means.

11. In a mechanical drier the combination with a rotatable outer shell, of an inner tube mounted within the outer tube and extending through the rear end of the outer tube and provided with a perforated head and having openings therein intermediate its ends, an annular flange adjacent to the said intermediate openings, an exhaust fan mounted outside of the drier, and connections between the inner tube and the exhaust fan.

12. In a rotary drier having a feed opening in the front end and a discharge opening in the rear end thereof, an inner tube constituting a channel for the withdrawal of moist vapors from the drier having external lifting channels thereon, and a non-rotatable member positioned within the drier as and for the purpose set forth.

13. In a drying apparatus communicating with a source of heat, an inner tube constituting a flue for the withdrawal of vapor from the drier mounted concentrically within the outer shell having its rear end extending to the rear end of the outer cylinder and provided with an opening for the admission of vapor, a rear exhaust, and a connection between the inner tube and the exhaust.

14. In a drying apparatus communicating with a source of heat, an inner tube constituting a flue for the withdrawal of vapor from the drier, provided with openings therein for the admission of vapor, a rear exhaust, a connection between the inner tube and the exhaust and an annular collar on the inner tube adjacent the openings whereby said openings are protected from the cascaded material.

15. In a mechanical drier, the combination of an outer shell communicating with a source of heat at its front end, an inner sectional tube constituting a flue for the withdrawal of vapor to the rear of the outer shell and having an opening in the front end thereof communicating with the outer shell, a rear exhaust, and a connection between the inner tube and the rear exhaust.

16. In a mechanical drier, the combination of an outer shell communicating with a source of heat at its front end, an inner sectional tube constituting a flue for the withdrawal of vapor from the outer shell provided with an opening therein communicating with the outer shell, a rear exhaust,

2. a connection between the inner tube and the rear exhaust, and peripheral openings in the rear end of the inner tube whereby any material therein will be discharged.
3. 17. In a mechanical drier, the combination of an outer shell communicating with a source of heat at its front end, an inner sectional tube constituting a flue for the withdrawal of vapor from the outer shell 10 provided with an opening therein communicating with the outer shell, a rear exhaust, a connection between the inner tube and the rear exhaust, and deflecting means in the drier.
4. 18. In a rotary drier, the combination of an outer cylinder provided with a feed inlet opening at its front end and a discharge outlet at its rear end, a flue centrally mounted in the outer cylinder and having an 20 opening at its forward end within the drier communicating with a source of heat, and a rear exhaust connected to the rear end of the drier having communication with the flue substantially as described.
5. 19. In a rotary drier the combination of an outer cylinder provided with a feed inlet opening and a discharge outlet, an inner cylinder mounted wholly within the outer cylinder and provided with an opening at 30 its forward end communicating with a source of heat, and a rear exhaust engaging the rear end of the drier and having communication with the rear end of the inner cylinder substantially as described.
6. 20. In a mechanical drier, the combination of an outer rotary cylinder having a feed opening and a discharge outlet therein, an inner tube centrally suspended in the outer cylinder comprising two connected 40 sections spaced apart from each other, and a rear exhaust engaging the rear end of the drier and having communication with the inner tube.
7. 21. In a rotary drier, the combination of an outer cylinder having an inlet opening 45 leading to a source of heat, and an inner cylinder centrally mounted in the drier provided with a front intake positioned substantially in line with and to the rear of the said inlet opening, said inner cylinder being adapted to conduct vapor from the outer cylinder to the atmosphere substantially as described.
8. 22. In a rotary drier, the combination of an outer cylinder having an inlet opening 55 at its front end leading to a source of heat and an outlet opening in the rear end thereof, and an inner cylinder provided with a front intake positioned slightly to the rear 60 of the said inlet opening and within the drier, said inner cylinder extending to the said outlet opening in the rear end of the outer cylinder.
9. 23. In a rotary drier, the combination of an outer cylinder having an inlet opening at 65 its front end leading to a source of heat, and peripheral openings in the rear end of the inner cylinder provided with a front intake positioned slightly to the rear of the said inlet opening and within the drier, said inner cylinder extending to the said outlet opening in the rear end of the outer cylinder.
10. 24. In a rotary drier, the combination of an outer cylinder having an inlet opening at its front end leading to a source of heat and an outlet opening in the rear end thereof, and an inner cylinder provided with a front intake positioned slightly to the rear of the said inlet opening and within the drier, said inner cylinder extending to the said outlet opening in the rear end of the outer cylinder, and external lifting blades peripherally mounted on the inner cylinder. 70
11. 25. In a rotary drier, the combination of an outer cylinder having an inlet opening at its front end leading to a source of heat and an outlet opening in the rear end thereof, and an inner cylinder provided with a front intake positioned slightly to the rear of the said inlet opening and within the drier, and a non-rotatable member 12 positioned within the drier substantially as described. 75
12. 26. In a rotary drier, the combination of an outer cylinder having an inlet opening at its front end leading to a source of heat and an outlet opening in the rear end thereof, and an inner cylinder provided with a front intake positioned within the drier and slightly to the rear of the said inlet opening, said inner cylinder extending to the said outlet opening in the rear end of the outer cylinder, and exhaust means located outside the drier communicating with the inner cylinder. 80
13. 27. In a rotary drier, the combination of an outer cylinder having an inlet opening at its front end leading to a source of heat and an outlet opening in the rear end thereof, and an inner cylinder provided with a front intake positioned slightly to the rear of the said inlet opening and within the drier, said inner cylinder extending to the said outlet opening in the rear end of the outer cylinder. 85
14. 28. In a rotary drier, the combination of an outer cylinder having an inlet opening at its front end leading to a source of heat and an outlet opening in the rear end thereof, and an inner cylinder provided with a front intake positioned slightly to the rear of the said inlet opening and within the drier, said inner cylinder extending to the said outlet opening in the rear end of the outer cylinder, and exhaust means located outside the drier communicating with the inner cylinder. 90
15. 29. In a rotary drier, the combination of an outer shell having an inlet opening leading to a source of heat and an outlet opening 95

ing in the rear end thereof, and an inner cylinder provided with a flared intake positioned adjacent the said inlet opening, said inner cylinder substantially extending 5 to the said outlet opening in the rear end of the shell.

30. In a rotary drier, the combination of an outer shell having an inlet opening leading to a source of heat and an outlet opening 10 in the rear end thereof, and an inner cylinder provided with a flared intake po-

sitioned adjacent the said inlet opening, said flared intake carrying a foraminous head substantially as described.

In testimony whereof, I have hereunto 15 signed my name in the presence of the two subscribed witnesses.
